LINK CHAIN FOR A BRACELET OR THE LIKE

Emil Rodriguez, New York, N. Y., assignor to
Jacoby-Bender, Inc., New York, N. Y., a corporation of New York

Application November 22, 1952, Serial No. 22,412

Term of patent 7 years

(Cl. D45—4)

To all whom it may concern:

Be it known that I, Emil Rodriguez, a citizen of the United States and a resident of New York, county and State of New York, have invented a new, original, and ornamental Design, for a Link Chain for a Bracelet or the like, of which the following is a specification, reference being had to the accompanying drawing forming a part thereof, in which:

Fig. 1 is a top plan view of the link chain, showing my new design;

Fig. 2 is a top plan view, on an enlarged scale, of one of the individual links of the chain of Fig. 1;

Fig. 3 is an end elevational view of the link of Fig. 2;

Fig. 4 is a side elevational view of the link of Fig. 2 taken from the left hand side of Fig. 2;

Fig. 5 is a side elevational view of the link of

Fig. 2, taken from the right hand side of Fig. 2; and

Fig. 6 is a side elevational view of the link chain of Fig. 1, but on a scale corresponding to Figs. 2 and 5.

I claim:

The ornamental design for a link chain for a bracelet or the like, as shown.
